(57) **CLAIM**

The ornamental design for an interlocking vent assembly for equalizing pressure in a compartment, as shown and described.

DESCRIPTION

FIG. 1 is an illustration of a perspective view of an installed interlocking vent assembly for equalizing pressure in a compartment;

FIG. 2 is an illustration of a side perspective view of an assembled and uninstalled interlocking vent assembly for equalizing pressure in a compartment;

FIG. 3 is an illustration of a top view of the interlocking vent assembly for equalizing pressure in a compartment, where the bottom view in an assembled configuration presents a 180 degrees planar rotated view of the top view with no different feature between the top view and the bottom view;

FIG. 4 is an illustration of a longitudinal side view of the interlocking vent assembly for equalizing pressure in a compartment;

FIG. 5 is an illustration of a top end side view of the interlocking vent assembly for equalizing pressure in a compartment; and,

FIG. 6 is an illustration of a bottom end side view of the interlocking vent assembly for equalizing pressure in a compartment.

In the drawings, the broken line showing of parts of the drawings is included for the purpose of illustrating use and environment and form no part of the claimed design.
